COIN CHANGING DEVICE

Jack S. Millard, San Antonio, Tex.

Application November 18, 1941, Serial No. 419,639

11 Claims. (Cl. 194—7)

This invention relates to coin changing devices.

An object of this invention is to provide a coin changing device which will automatically change a coin upon discharge of the coin in the machine.

Another object of this invention is to provide in a device of this kind means for retaining the last coin changed in view so that should any dispute arise as to the amount of change delivered by the device, a check-up can easily and quickly be made.

A further object of this invention is to provide an electrically operated device of this kind wherein the inserted coin closes an electric circuit to the operating motor so as to thereby complete a coin changing cycle.

A further object of this invention is to provide a coin changing device which includes a locking means for the inserted coin chute so that a second coin cannot be inserted while the machine is in the act of changing a prior inserted coin.

A further object of this invention is to provide a coin changing device including a plurality of coin delivering slides each of which is slidable below a coin magazine and an improved means whereby certain of the slides are operated by means of an inserted coin.

A further object of this invention is to provide a coin changing device which is relatively simple in construction and which is positive in its action so as to provide for the accurate delivery of the amount of change for a predetermined inserted coin.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a horizontal sectional view partly broken away and in detail of a coin changing device constructed according to an embodiment of this invention.

Figure 2 is a fragmentary vertical sectional view taken substantially through the center of the device.

Figure 3 is a sectional view taken on the line 3—3 of Figure 1.

Figure 4 is a sectional view taken on the line 4—4 of Figure 3.

Figure 5 is a sectional view taken on the line 5—5 of Figure 3.

Figure 6 is a sectional view taken on the line 6—6 of Figure 1.

Figure 7 is a sectional view taken on the line 7—7 of Figure 1.

Figure 8 is a sectional view taken on the line 8—8 of Figure 7.

Figure 9 is a sectional view taken on the line 9—9 of Figure 8.

Figure 10 is a diagrammatic view of the electric circuits embodied in this invention.

Figure 11 is a sectional view taken on the line 11—11 of Figure 3.

Figure 12 is a horizontal sectional view partly broken away taken on the line 12—12 of Figure 2.

Figure 13 is a fragmentary sectional view taken on the line 13—13 of Figure 12, and

Figure 14 is a fragmentary sectional view taken on the line 14—14 of Figure 12.

Referring to the drawings the numeral 15 designates generally a housing structure, which has mounted therein a coin changing mechanism including a coin delivery means generally designated as 16, and an electrically operable selector mechanism generally designated as 17. The delivery mechanism 16 comprises a series of outer vertically disposed tubular magazines 18, 19, 20, 21 and 22. The coins in the magazines 18 to 22 inclusive are adapted to gravitantly move downwardly in the magazines as the lowermost coins in the magazines are discharged therefrom.

The magazines 18, 19, and 20 are secured to the top wall 23 of a slide housing generally designated as 24, and the housing 24 has slidably mounted therein a plurality of horizontally slid- 35 able coin delivery slide members 25, 26, and 27. The slide member 25 is slidable beneath the magazine 18, the slide member 26 is slidable beneath the magazine 19 and the slide member 27 is slidable beneath the magazine 20. The housing 24 is provided with a bottom wall 28 having openings 29, 30, and 31 therein which overlie a coin delivery chute 32. The coin delivery chute 32 is formed of a downwardly inclined bottom wall 33. A vertical wall 34, and upstanding side walls 35, and the chute 32 communicates at its lower or forward end with a delivery opening 36 formed in the front wall 37 of the housing 15.

The housing 24 has fixed to the bottom wall 28 thereof a block 38 which is disposed beneath the lower end of the magazine 19.

The space between the upper face of the block 38 and the inner face of the top wall 23 of the housing 24 is sufficient to permit a small coin such as a dime to slide between the block 38 and the top wall 23. The slide 19 is of a thick-

ness sufficient to effect movement of the lowermost coin in the magazine 19, so that this coin will be moved forwardly and will then gravitatingly drop downwardly into the interior of the housing 23, and downwardly through a delivery opening 30 in the bottom wall 28 which is positioned forwardly of the block 38. The slide 27 is of substantial thickness, and in the present instance is of a thickness substantially equal to the distance between the top and bottom walls 23 and 28 respectively, so that five pennies may engage in the opening 40 which is formed in the forward end portion of the slide 27 and which is adapted to normally register with the lower open end of the magazine 20. The magazine 20 is adapted to receive pennies, and upon forward movement of the slide 27 the pennies in the recess 40 are adapted to move with the slide 27 and then drop downwardly through a delivery opening 31 formed in the bottom wall 28 forwardly of the magazine 20. The slide 25 is formed with an opening 42 registering with the lower end of the magazine 18 and the single coin engaging within the opening 42 is adapted to be discharged through an opening 43 formed in the bottom wall 28 forwardly of the magazine 18.

The magazine 18 is adapted to receive half dollars, and one coin of this denomination is moved from beneath the lower end of the magazine 18 and then discharged into the delivery opening 43 from where the coin drops into the delivery chute or hopper 32. A guide or slide housing 44 is disposed in laterally spaced relation to the housing 24, being the second one of the outer pair of delivery housings and is secured to the lower ends of the two magazines 21 and 22. The housing 44 has slidable therein a pair of slide members 45 and 46 which are slidable beneath the lower ends of the magazines 21 and 22. The slide members 45 and 46 may be constructed integral with each other and each slide member 45 and 46 is adapted to have an opening therethrough registerable with the lower ends of the magazines 21 and 22 when the slide members are in their normal coin receiving position.

The slide members 45 and 46 are similar to the slide members 25, 26, and 27 with the exception that the slide member 46 is substantially thicker than the slide member 45, so that when the slide member 46 is moved forwardly two nickels will be moved out from beneath the stack of nickels which are positioned in the magazine 22, for delivery through a delivery opening 61 formed in the housing 44. The magazine 21 is adapted to receive quarters and the slide 46 is adapted to move only one quarter from beneath the stack of coins positioned within the quarter magazine 21, for delivery through a delivery opening 62 in the housing 44. The outer pair of housings 24 and 44 are associated with each other and the slide members carried thereby are movable as a unit so that when a dollar is inserted in the coin controlled slide operating mechanism, the slides in the housings 24 and 44 will deliver coins of several denominations making a total of one dollar.

The coin delivery mechanism also includes a second pair of guide housings 47 and 48 which are disposed inwardly from the housings 24 and 44. The housing 47 has secured to the upper side thereof a pair of upstanding coin magazines 49 and 50. The magazine 49 is adapted to receive dimes, whereas the magazine 50 is adapted to receive pennies. The housing 48 has secured to

the upper side thereof a pair of upstanding magazines 51 and 52. The magazine 51 is adapted to receive nickels, whereas the magazine 52 is adapted to receive quarters. The housing 47 has slidable therein a pair of coin delivering slides 53 and 54 which may be formed integral with each other and the slide 53 is adapted to deliver one dime into a delivery opening 55 which is formed in the bottom wall of the housing 47.

10 The housing 47 is also provided with a second delivery opening 56 forwardly of the magazine 50 through which the pennies moved forwardly by the slide 54 are adapted to drop for delivery to the person inserting the coin in the coin mechanism through the delivery chute or hopper 32.

15 The slide 54 is adapted to move five pennies forwardly from beneath the lower end of the stack of coins disposed in the coin magazine 50. The housing 48 has slidable therein a pair of integral slide members 57 and 58 and the housing

20 48 is formed with a delivery opening 59 forwardly of the magazine 51 through which two nickels are adapted to drop. The housing or guide 48 is also formed with a second delivery opening 60 forwardly of the magazine 51 through which one quarter is adapted to drop when this one quarter is moved forwardly from beneath the stack of coins in the magazine 52 upon forward movement of the slide 58.

25 30 An inner slide housing or guide 63 is disposed between the housings 47 and 48 and has slidable therein slide members 64, 65, and 66. The housing 63 has secured to the upper side thereof in upstanding relation coin magazines 67, 68, and

35 69. The coin magazine 68 is disposed above the slide 65 and the coin magazine 69 is disposed above the slide 66. The slide 64, 65, and 66 may be formed integral with each other, and may be provided with suitable openings for registry with

40 the lower ends of the magazines 67, 68, and 69 respectively, so that when the slides 64, 65, and 66 are moved forwardly the coins carried therewith will be discharged into a delivery opening 70 which is common to all of the slides 64, 65, and

45 66 and which communicates with the hopper or delivery chute 32. The slide 64 is adapted to move one dime from beneath the stack of dimes in the magazine 69; the slide 65 is adapted to move five pennies from beneath the stack of pennies in the magazine 68 and the slide 66 is adapted to move two nickels from beneath the stack of coins in the magazine 60 so that proper change for a quarter will be delivered from the magazines 67, 68, and 69 through the delivery hopper or chute 32.

50 55 An intermediate pair of slide housings or guides 71 and 72 are disposed between the housings 47 and 48 and have secured in upstanding relation thereto coin magazines 73 and 74 respectively.

60 60 The housing or guide 71 has slidable therein a coin delivery slide 75 for delivering five pennies from the penny magazine 73 to a delivery opening 76 formed in the forward lower portion of the housing 71. The housing 72 has slidable therein a coin delivering slide 77 which is slidable beneath the lower end of the magazine 74 for delivering one nickel from the nickel magazine 74 to a delivery opening 78 formed in the forward portion of the housing or guide 72. The delivery openings 76 and 78 communicate with the hopper or

65 70 chute 32 for delivering the ejected coins to the person inserting one dime in the coin slot to be hereinafter described.

75 A centrally disposed guide housing 79 is disposed between the two housings 71 and 72 and

forwardly of the housing 63. The housing 79 has secured in upstanding relation thereto a coin magazine 80 which is adapted to receive pennies for delivery to the delivery chute or hopper 32 when a coin delivering slide 81 which is slidable in the housing 79 is moved forwardly from beneath the magazine 80. The coins which are five in number and which are moved forwardly by the slide 81 are discharged into a delivery opening 82 formed in the forward portion of the housing 79 and which communicates with the delivery hopper or chute 32.

The coin selector mechanism 17 includes a vertically disposed coin receiving chute generally designated as 83 which is substantially V-shaped in side elevation and is open at its upper end. The upper end of the chute or coin guide 83 is disposed beneath a hinged closure or door 84 carried by the top wall 85 of the housing 15. The closure 84 is provided with a coin slot 86 communicating with the upper or large end of the chute 83. The lower or small end of the coin receiving chute 83 is secured by means of a bracket 87 to a coin receiver 88 mounted on the bottom wall 89 of the housing 15 rearwardly of the coin delivery mechanism 16. The guide 83 comprises an inner pair of side walls 90 which are of insulated construction and are secured at one edge thereof to a vertical end wall 91 which is also of insulated construction. A metallic outer housing or jacket encloses the insulated side walls 90 and includes a pair of outer side walls 92 and 93 which are connected together by an end wall 94. The end wall 94 is disposed opposite from the end wall 91. The end walls 91 and 94 are disposed in downwardly convergent relation as shown in Figure 3, the angular relation of these walls one to another being such as to effect a wedging and stopping of coins of different denominations as these coins move downwardly in the guide 83.

The end wall 91 adjacent the upper portion thereof is provided with a coin delivery opening 95 which is of sufficient length to permit the delivery of a dollar therethrough. A contact 96 is disposed in inwardly projecting relation with respect to the opening 95, projecting inwardly a slight distance from the inner wall 91 for engagement with a dollar which is dropped into the chute or guide 83. The contact 96 constitutes a means for limiting the downward movement of a dollar in the guide 83 and is carried by a U-shaped supporting member 97. The supporting member 97 includes a bight portion 98 carried by parallel arms 99 which are slidably in an opposed pair of upwardly and rearwardly inclined guide members 100 and 101 positioned on the opposite sides of the housing or jacket formed by the walls 92, 93, and 94.

The guide structures 100 and 101 are formed with guide channels 102 and 103 respectively within which the parallel arms 99 slidably engage. The guide member 93 is also formed with an opening 104 below the opening 95 which is adapted to confront a half dollar. A contact member 105 which is carried by the bight portion 106 of a U-shaped support is adapted to project inwardly a slight distance through the opening 104 for engagement with a half dollar and for limiting the downward movement of the half dollar within the guide 83. The bight portion 106 includes a pair of parallel arms 107 which are slidably in a pair of opposed guide members 108 and 109 carried by the side walls 92 and 93.

The coin chute or guide 83 is also formed with

a coin delivery opening 110 disposed below the opening 104 which is adapted to confront a quarter engaging with the guide 83. A contact member 111 carried by the bight 112 of a U-shaped member 113 is adapted to project a slight distance through the opening 110 for engagement with the edge of a quarter and limit the downward movement of the quarter within the guide 83. The U-shaped support 113 includes a pair of parallel arms or legs 114 which are slidable in outwardly opening guide members 115 and 116 carried by the side walls 92 and 93 respectively.

The guide member 83 is formed with a delivery opening 117 below the opening 110 which is adapted to confront a nickel disposed in the guide 83. A contact member 118 which is carried by the bight portion 119 of a U-shaped member 120 is adapted to project slightly into the guide 83 through the opening 117 thereof for engagement with the edge of a nickel and to limit the downward movement of the nickel within the guide 83. The parallel arms 121 of the U-shaped member 120 are slidable in outwardly opening guides 122 and 123 which are fixed to the side walls 92 and 93 respectively and are inclined to the horizontal.

The guides 108, 109, 115, and 116 are also inclined to the horizontal. A lowermost opening 124 is formed in the end wall 91 below the opening 117 and is adapted to confront a dime engaging within the lower portion of the guide 83. An inwardly projecting stop member 125 may be fixed to the lower end portion of the guide 83 in order to limit the downward movement of the smallest coin or dime within the guide 83. A contact member 126 which is carried by the bight 127 of a U-shaped support 128 is adapted to project slightly into the interior of the guide 83 for engagement with the peripheral edge of a dime to form an electric contact with the dime and also to limit the downward movement of the dime within the guide 83. The U-shaped support 128 includes a pair of parallel arms or legs 129 which are slidably in opposed outwardly opening guide members 130 and 131 which are inclined to the horizontal and are fixed to the side walls 92 and 93. The U-shaped member 97 has pivotally connected to the free ends of the parallel arms 99 thereof, a pair of links 132 and 133.

The link 132 at its forward or lower end is pivotally connected to an arm 134 which is fixed relative to the integral slides 25, 26 and 27. A guide roll 135 is rotatably carried by the housing 24 on the inner side thereof and the arm 134 engages the roller 135. The arm 134 is adapted to move in a horizontal plane whereas the link or connecting member 132 moves in an upward and rearward direction.

60 The link 133 at its forward end is pivotally connected to an arm 136 which is fixed relative to the two integral slides 45 and 46. The U-shaped member formed by the bight 106 and the parallel arms 107 has pivotally connected to the parallel arms 107 thereof a pair of downwardly and forwardly inclined links 137 and 138. The link 137 at its lower or forward end is pivotally connected to an arm 139 which is fixed relative to the integral slides 53 and 54 and the forward or lower end of the link 138 is pivotally connected to an arm 140 which is fixed relative to the integral slides 57 and 58. The parallel arms 114 of the U-shaped member 113 are pivotally connected to a pair of links 141 and 142

which at their lower forward ends are connected to arms 143 and 144 respectively which are fixed relative to the integral slides 64, 65, and 66. The arms 143 and 144 are disposed on opposite sides of the housing 79 as shown in Figure 1.

The U-shaped member 120 has pivotally connected to the lower ends of the parallel arms 121 thereof, a pair of connecting links 145 and 146. The links 145 and 146 at their lower forward ends are disposed in convergent relation and are fixed together. The convergent ends of the links 145 and 146 are pivotally connected to a rearwardly extending arm 147 which is fixed relative to the slide 81.

The U-shaped member 128 has pivotally connected to the parallel legs 129 thereof a pair of downwardly and forwardly inclined links or connecting members 148 and 149. The lower forward end of the link 148 is pivotally connected to a rearwardly extending arm 150 fixed relative to the slide 75. The lower forward end of the link 149 is pivotally connected to the rear end of an arm 151 which is fixed relative to the slide 77.

In order to provide a means whereby the inserted coins which are dropped into the chute or guide 83 may be ejected from the chute or guide 83, I have provided a coin ejecting and circuit closing structure generally designated as 152. The coin ejecting structure 152 includes an upwardly extending contact carrier 153 which is pivotally mounted as at 154 on a bearing structure 155 fixed to the bottom wall 89. The carrier 153 has secured thereto a longitudinally arcuate contact member 156 which is movable through an opening 157 formed in the end wall 94. The inner end of the contact member 156 is disposed in a position for engagement with a dollar and is disposed opposite from the contact 96 so that when a dollar is inserted in the guide 83, this coin will bridge the two contacts 96 and 156, and thereby close an electric circuit within which these contacts are interposed.

A second longitudinally arcuate contact member 158 is fixed to the carrier 152 below the contact 156 and is movable through an opening 159 formed in the end wall 94 substantially opposite the opening 104 and confronting the contact 105. When a half dollar is inserted in the guide 83 this coin is adapted to bridge the space between the two contacts 105 and 158 so as to close the electric circuit to the electric operator for the carrier 152. The third contact 160 is fixed to the carrier 152 below the contact 158 and is movable through an opening 161 formed in the end wall 94 substantially opposite the opening 110. When a quarter is inserted in the guide 83, this coin is adapted to wedge between the two contacts 111 and 160 so as to thereby bridge the space between these contacts and close an electric circuit to the electric operator for swinging or moving the carrier 152. Another longitudinally arcuate contact 162 is fixed to the carrier 152 and is movable through an opening 163 formed in the end wall 94 substantially opposite the opening 117. When a nickel is inserted in the guide 83, this coin is adapted to wedge between the two contacts 118 and 162 for closing the electric circuit to the operator for moving the carrier 152. A lower longitudinally arcuate contact 164 is fixed to the carrier 152 below the contact 162 and is movable through an opening 165 formed in the lower portion of the end wall 94.

The opening 165 is substantially opposite the opening 124 and when a dime is inserted in the

guide 83 this coin is adapted to wedge between the two contacts 126 and 164 for closing an electric circuit to the operator for the carrier 152.

The upper portion of the carrier 152 is swingable in a substantially sector shaped housing generally designated as 166 including a pair of side walls 167 and 168 disposed in parallel relation. The side walls 167 are formed adjacent the upper end portion thereof with a longitudinally arcuate guide 169 within which a roller 170 carried by the carrier 152 is adapted to movably engage. The side walls 167 are also formed with longitudinally arcuate guide channels 171, 172, 173, and 174 within which rollers 175, 176, 177, and 178 are adapted to movably engage. The channels 171, 172, 173, and 174 are correlated with contact members 158, 160, 162, and 164 respectively.

In order to provide a means whereby the carrier 152 may be rocked rearwardly to a coin ejecting position upon insertion of a coin within the guide 83, I have provided an electric motor 179 which is disposed rearwardly of the guide 83. The motor 179 has mounted on the shaft 180 thereof a plate 181 having an eccentrically disposed pin 182 mounted therein. A U-shaped carrier operator 183 has the parallel arms 184 thereof disposed on opposite sides of the guide 83 and the housing 166.

The bight 185 of the operator 183 has a rearwardly extending arm 186 fixed thereto which is pivotally mounted at its rear end of the crank pin 182. The forward or free ends of the parallel arms 184 of the U-shaped operator 183 are pivotally connected to a pair of oppositely extending bars 187 which are fixed to the carrier 152 at a point below the upper end thereof. In Figure 10 there is disclosed diagrammatically the electric circuits associated with the motor 179 and the contacts hereinbefore described. These electric circuits include a conductor 188 connected to one side of the motor 179 and connected by means of conductors 189, 190, 191, 192 and 193 to the contacts 96, 105, 111, 118, and 126 respectively. The other side of the motor 179 is connected by means of a conductor 194 to the carrier 152. In this manner when a coin is inserted in the guide 183 this coin will bridge the correlated pair of contacts and effect a closing of the electric circuit to the motor 179. When the carrier 152 is moved to its rearmost position the coin engaging between the engaging contacts will drop down, and the electric circuit to the motor 179 will thereby be broken.

In order to provide for the continued operation of the motor 179 after the coin is released from between a pair of contacts, I have provided a stationary resilient contact 195 which is connected by means of a conductor 196 to the conductor 188. The contact 195 is mounted on a plate 197 mounted on the front wall 198 of the coin receiver 88 which is positioned below the rear contacts 96, 105, 111, 118 and 126. A second resilient contact 199 is fixed to the rear side of the carrier 152 in a position to engage the stationary resilient contact 195 after the carrier 152 has initially started its coin ejecting operation.

The two contacts 195 and 199 are shown more clearly in Figure 11 wherein it will be noted that these contacts are in disengaged position when the carrier 152 is in its normal forward position so that the electric circuit to the motor 179 within which the contacts 195 and 199 are interposed will be broken just prior to the time that the carrier 152 reaches its foremost or normal posi-

tion. By means of the two contacts 195 and 199 the continued operation of the motor 179 is assured so as to provide for one complete revolution of the crank plate 181 and for the complete cycle of the operator 183 which is connected to the carrier 152. In order to provide for a return of the several coin delivery slides to their normal positions beneath the correlated coin magazines when the carrier 152 has returned to its normal forward position, which is the position shown in Figure 3, I have provided a spring 200 which is connected at one end to the slide member 25, 26, and 27 and the other end to the front wall 37 of the housing 15.

The slide members 45 and 46 are also returned to their normal position beneath the magazines 21 and 22 by means of a spring 201 fixed at its rear end to the slide 46, and its forward end to the front wall 37. The slides 53 and 54 are returned to their normal position beneath the magazines 49 and 50 by means of a spring 202 which is connected to the slide 53 and to the front wall 37. The slide members 57 and 58 which are correlated with the slide members 53 and 54 are returned to their normal position beneath the magazines 51 and 52 by means of a return spring 203 connected at one end to the slide 57 and the other end to the front wall 37.

The slides 64, 65, and 66 are returned to their normal positions beneath the magazines 67, 68, and 69 respectively by means of return springs 204 and 205. The slides 75 and 77 are returned to their normal positions beneath the magazines 73 and 74 by means of return springs 206 and 207. The slide 81 is also returned to its normal position beneath the magazine 80 by means of a return spring 208. By means of the slide return springs hereinbefore described, the contacts 96, 105, 111, 118, and 126 are placed under tension during their rearward and upward movement and also promptly returned to their normal positions with respect to the guide 82 so that when the carrier 152 is in its normal forward position the contacts 96, 105, 111, 118 and 126 are also put in their normal positions.

The coin receiver 88 which is adapted to receive the inserted coins which are to be changed, comprises a receptacle formed of side walls 209, 210, a rear wall 211, bottom wall 212a and front wall 198. A top wall 212 is fixed within the receptacle 88 below the upper end thereof and is formed with an opening 213. The opening 213 is closed by means of a pair of doors 214 and 215 which are hingedly secured to the top wall 212 by means of hinge members 216, and 217 respectively. The doors 214 and 215 are adapted to gravitatingly swing downwardly into an open position so as to permit a coin engaging on the upper face thereof to drop into the receiver 88. The doors 214 and 215 are resiliently and normally held in a closed position by means of a pair of pivoted levers or arms 218 and 219 respectively which are pivotally mounted at their rear ends on pivot members 220 and 221 respectively.

The pivot members 220 and 221 engage through the top wall 212. A spring 222 mounted on a pin 223 carried by the top wall 212 bears against the forward end and outer edge of the door closing arm or lever 218 so as to constantly urge this arm inwardly to effect movement of the door 214 to a closed position. The arm or lever 219 is constantly urged inwardly to a door closing position by means of a spring 224 mounted on a pin 225 carried by the top wall 212. The arm or lever 218 is formed on its inner edge thereof with

5 a downwardly bent door engaging cam 226 which is adapted to engage the underside of the door 214, when this latter door is in an open position, and the arm or lever 218 is moving inwardly to effect closing or raising of the door 214.

The arm or lever 219 is provided with a door closing cam 227 on its inner edge thereof and adjacent the forward portion for engagement with the under side of the door 215 so as to facilitate 10 the raising of the door 215 when the door 215 is in an open position. The forward end of the arm or lever 218 is provided with an integral and obtusely disposed extension 228, and a pivoted arm operating member 229 is pivotally mounted 15 as at 230 on the extension 228, and extends obtusely with respect to the arm or lever 218.

A spring 231 carried by the extension 228 bears against the outer edge of the arm or lever operator 229 so as to normally maintain the extension 20 or operator 229 in alignment with the extension 228. The arm or lever 219 is formed at its forward end with an obtusely disposed integral extension 232, and a lever or arm operator 233 is pivotally mounted as at 234 on the extension 232 25 and is constantly urged to an aligning position with respect to the extension 232 by means of a spring 235. The two pivoted operators or lever extensions 229 and 233 are disposed in forwardly convergent relation and are provided at their forward ends with enlarged heads 236 and 237 respectively. A V-shaped lever operator 238 is carried by a rearwardly extending support 239 which is fixed to the rear side of the carrier 152 and is disposed in a position for engagement with 30 the head members 236 and 237, so that upon rearward swinging movement of the carrier 152 the levers 218 and 219 will be swung outwardly to a door releasing position. The supporting member 239 has fixed thereto a pair of laterally extending pins 240 which are adapted to engage 35 and rest upon a supporting track 241 disposed forwardly of the receptacle 88.

The track 241 is supported in forwardly spaced relation with respect to the receptacle 88 by 45 means of upwardly and forwardly extending supporting braces 242 and 243. The upper end of the guide 83 is fixed to the lower wall 244 of a depending housing 245 which is disposed below the under side of the closure 84. The bottom wall 244 is provided with a slot or opening 246 registering with the open upper end of the guide 233. A pair of resilient flaps 247 are positioned within the housing 245 and are normally disposed in a horizontal position with their adjacent edges in substantial contact so as to thereby close the coin slot 86. In order to provide a means whereby a second coin cannot be inserted in the guide 83 while the carrier 152 is moving either rearwardly or forwardly, I have provided a guide closing or locking plate 248 which is fixed at one end to the inner side of the carrier 152 and is slidably through an opening 249 formed in the end wall 94. The guide closing or locking member 248 is of resilient construction, being normally longitudinally bowed, and is adapted to slide over the surface of the bottom wall 244 of the housing 245 for closing the opening of the slot 246.

In the use and operation of this coin changing device the various coin magazines may be filled with coins by raising the closure 84 which is normally locked by means of a locking structure 250. When the magazines have been filled, the coins positioned therein will engage the respective slides or coin delivery members positioned

therebeneath. In the event it is desired to change a dollar this coin is inserted in the coin slot 86 and moved downwardly until the coin engages and wedges between the two contacts 96 and 156. The dollar will engage the contact 156 adjacent the lower portion thereof and will engage the contact 156 adjacent the upper portion thereof. As soon as the dollar engages between the two contacts 96 and 156 this inserted coin will close the electric circuit embodying the conductors 189, 188, and 194 to the electric motor 179. The motor 179 will thereupon swing the carrier 152 rearwardly and as the carrier 152 swings rearwardly the coin will roll with respect to the two contacts 96 and 156, rolling beneath the contact 96 after the coin passes through the opening 91. The rearward movement of the carrier 152 will pull the yoke or U-shaped member 97 rearwardly and upwardly, which will effect rearward movement of the links 132 and 133. Rearward and upward movement of the links 132 and 133 will pull the slides 25—26—27 and the slides 45 and 46 respectively rearwardly to a coin delivering position.

Rearward movement of the slides 25, 26, and 27 will effect delivery of the coins to the delivery chute or hopper 32 and rearward movement of the slides 45 and 46 will effect delivery of the coins to the delivery chute or hopper 32. As the slides 25—26—27 are moved rearwardly the spring 200 will be tensioned so that immediately upon dropping of the dollar from between the two contacts 96 and 156 the spring 200 will return the integral slides 25—26—27 to their normal forward position beneath the magazines 18, 19 and 20. The same operation is effected by means of the spring 201 with respect to the slides 45 and 46. After the dollar or other coin has been delivered down onto the closed doors 214 and 215 of the receiver 88, the motor 179 will continue in operation by reason of the closing of the circuit thereto which is effected by the contacts 195 and 199. The contact 199 is connected by a conductor 251 to the conductor 194 so that when the contacts 195 and 199 are in engagement with each other a circuit will be closed from the contact 195 through the conductor 196 and conductor 188 to one side of the motor 179. The other side of the motor 179 is interposed in the closed circuit by means of conductors 194 and 251, the latter being connected to the contact 199.

When the carrier 152 initially moves rearwardly to an inserted coin ejecting position and a change delivering position, the lever opening or swinging wedge 238 will swing the levers 218 and 219 outwardly to a door releasing position thereby permitting the doors 214 and 215 to gravitantly swing downwardly to an open position. This swinging movement is provided prior to the dropping of the coin which closes the circuit to the motor 179. When the wedge member 238 passes the heads or forward ends 236 and 237 of the pivot members 229 and 233, the levers 218 and 219 will be promptly returned to a door closing position by the springs 222 and 224. At the time the inserted coin drops down from between the two contacts 96 and 156, as an example the doors 214 and 215 will be in a closed position in view of the fact that at this time the wedge shaped lever operator 238 will be positioned inwardly of the pivoted arms 229 and 233; the inserted coin which is at this time effecting operation of the change delivering slides will drop onto the closed doors 214 and 215 and will stay

on the upper sides of these doors until a subsequent coin is inserted in the guide 83.

By this means the owner of the change mechanism will be able to determine the value of the inserted coin, so that if any coin magazine should be empty and an insufficient number of coins be delivered to the delivery chute 32, the owner of the device may promptly make up the deficiency and may also resupply the empty coin magazine. 5 10 15

10 The disposition of the last coin changed on the closed doors 214 and 215 also provides a means whereby the person desiring the change and receiving the same, cannot dispute the amount of change received.

15 When the wedge shaped member 238 returns to its forward position upon forward swinging of the carrier 152, the levers 218 and 219 will remain in their door locking position by reason of the swinging or pivoting of the lever extensions 229 and 230 without movement of the levers 218 and 219. This is accomplished by providing the springs 231 and 235 of substantially lighter tension than the springs 222 and 224. In this manner the levers 218 and 219 are only swung outwardly to a door released position when the wedge shaped operator 238 is moved inwardly.

20 After the carrier 152 on its return stroke moves forward to a point where the two contacts 195 and 199 are in disengaged position, so as to break the electric circuit to the motor 179, the carrier 152 continues forwardly to the end of its movement by means of an adjustable weight 252, which is adjustably mounted by means of a set screw 253 on an elongated support 254. The support 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 slide, a second series of vertically spaced apart combined plungers and contact members, each one of said second series of plungers being disposed in confronting and spaced relation with respect to a plunger of said first series, said second series of plungers being spaced from said first series of plungers a distance such that a coin will wedge between a plunger of said first series and a confronting plunger of said second series of plungers, a motor operator connected with said second series of plungers, means connecting one side of said operator with said first series of plungers, means connecting the other side of said operator with said second series of plungers, a coin wedging between a pair of confronting plungers of each series constituting a bridging element for closing the electric circuit to said operator, and initially open circuit closing means active after said second series of plungers have started movement on the inserted coin ejecting cycle for maintaining a closed circuit to said operator after the inserted coin has been ejected from between said pair of plungers to thereby effect return of said second series of plungers to inoperative position.

3. A coin change delivering device comprising a plurality of vertically disposed coin magazines, a coin slide below each magazine, a coin guide for receiving a coin to be changed, opposed pairs of coin ejecting plungers movable relative to said guide for ejecting a coin therefrom, means connecting certain of said plungers with said slides whereby movement of selected ones of said certain plungers will effect movement of a slide to change delivering position, means connecting the remaining ones of said plungers together for movement in unison, a coin inserted in said guide wedging between an opposed pair of plungers, means for moving said remaining plungers to thereby eject the coin wedged therebetween and simultaneously move the slide correlated with one of said plungers to change delivering position, a coin receiver below said coin guide, a pair of normally closed doors carried by the upper end of said receiver, and means correlated with said connecting means and said doors for releasing said doors for movement of the latter to open position upon initial movement of said remaining plungers to coin ejecting position.

4. A coin change delivering device comprising a plurality of vertically disposed coin magazines, a coin slide below each magazine, a coin guide for receiving a coin to be changed, opposed pairs of coin ejecting plungers movable relative to said guide for ejecting a coin therefrom, means connecting certain of said plungers with said slides whereby movement of selected ones of said certain plungers will effect movement of a slide to change delivering position, means connecting the remaining ones of said plungers together for movement in unison, a coin inserted in said guide wedging between an opposed pair of plungers, means for moving said remaining plungers to thereby eject the coin wedged therebetween and simultaneously move the slide correlated with one of said plungers to change delivering position, a coin receiver below said coin guide, a pair of normally closed doors carried by the upper end of said receiver, and means correlated with said connecting means and said doors for releasing said doors for movement of the latter to open position upon initial movement of said remaining plungers to coin ejecting position, said latter means including means for moving said doors to closed position prior to the release of an ejected

coin whereby the last ejected coin will remain in view on top of said doors.

5. A coin change delivering device comprising a plurality of vertically disposed coin magazines, a coin slide below each magazine, a coin guide for receiving a coin to be changed, opposed pairs of coin ejecting plungers movable relative to said guide for ejecting a coin therefrom, means connecting certain of said plungers with said slides whereby movement of selected ones of said certain plungers will effect movement of a slide to change delivering position, means connecting the remaining ones of said plungers together for movement in unison, a coin inserted in said guide wedging between an opposed pair of plungers, means for moving said remaining plungers to thereby eject the coin wedged therebetween and simultaneously move the slide correlated with one of said plungers to change delivering position, a coin receiver below said coin guide, a pair of doors hingedly carried by the upper portion of said receiver and gravitatingly movable to an open position, spring-pressed means normally maintaining said doors in closed position, and release means carried by said connecting means engageable with said spring-pressed means for effecting release of said doors upon movement of said remaining plungers to coin ejecting position.

6. A coin change delivering device comprising a plurality of vertically disposed coin magazines, a coin slide below each magazine, a coin guide for receiving a coin to be changed, opposed pairs of coin ejecting plungers movable relative to said guide for ejecting a coin therefrom, means connecting certain of said plungers with said slides whereby movement of selected ones of said certain plungers will effect movement of a slide to change delivering position, means connecting the remaining ones of said plungers together for movement in unison, a coin inserted in said guide wedging between an opposed pair of plungers, means for moving said remaining plungers to thereby eject the coin wedged therebetween and simultaneously move the slide correlated with one of said plungers to change delivering position, a coin receiver below said coin guide, a pair of doors hingedly carried by the upper portion of said receiver and gravitatingly movable to an open position, spring-pressed means normally maintaining said doors in closed position, and release means carried by said connecting means engageable with said spring-pressed means for effecting release of said doors upon movement of said remaining plungers to coin ejecting position.

7. A coin change delivering device comprising a plurality of vertically disposed coin magazines, a coin delivering slide below each magazine, a coin guide for receiving a coin to be changed, coin ejecting means movable transversely through said guide for ejecting a coin therefrom, slide moving members confronting said ejecting means and spaced from and confronting the latter whereby an inserted coin will wedge between a slide moving member and a confronting ejecting means, means connecting each member with a slide, a receiver below said guide, closure means for said receiver, closure closing means normally maintaining said closure means in closed position whereby an ejected coin will rest on said closure means, and means correlated with said closure closing means and said operating means whereby

said closure closing means will remain in normal position when said ejecting means is returning to inoperative position.

8. A coin changing device comprising a plurality of vertically disposed coin magazines, a coin delivering slide below each magazine, a coin guide for receiving a coin to be changed, said guide including a pair of truncated V-shaped insulated inner side walls disposed in spaced apart relation, an insulated end wall formed with a plurality of vertically spaced apart openings for the passage of coins of different values, a pair of outer metallic walls fixed to said inner side walls, a metallic end wall fixed to said outer walls and formed with a plurality of vertically spaced apart openings opposite said first openings, contacts disposed loosely in each of said first openings, means connecting each contact with a slide, contacts confronting said first contact spaced from the latter and loosely engaging in said second openings, a common carrier for said second contacts, means supporting said carrier for movement whereby said second contacts may be moved inwardly of said guide, a motor operator for said carrier, means connecting said operator with said carrier, and an electric circuit for said operator within which said first and second contacts are interposed, said first and second contacts being spaced apart a distance such that a coin will wedge therebetween and thereby close said circuit.

9. A coin changing device comprising a plurality of vertically disposed coin magazines, a coin delivering slide below each magazine, a coin guide for receiving a coin to be changed, said guide including a pair of truncated V-shaped insulated inner side walls disposed in spaced apart relation, an insulated end wall formed with a plurality of vertically spaced apart openings for the passage of coins of different values, a pair of outer metallic walls fixed to said inner side walls, a metallic end wall fixed to said outer walls and formed with a plurality of vertically spaced apart openings opposite said first openings, contacts disposed loosely in each of said first openings, means connecting each contact with a slide, means supporting said connecting means for sliding movement at an angle to the vertical, contacts confronting said first contact spaced from the latter and loosely engaging in said second openings, a common carrier for said

second contacts, means supporting said carrier for vertical swinging movement whereby said second contacts may be moved inwardly of said guide, a motor operator for said carrier, means connecting said operator with said carrier, and an electric circuit for said operator within which said first and second contacts are interposed, said first and second contacts being spaced apart a distance such that a coin will wedge therebetween and thereby close said circuit.

10. A coin change delivering device comprising a plurality of coin magazines, a coin delivering slide for each magazine, a coin guide for receiving a coin to be changed, a series of coin engaging plungers movable relative to said guide means connecting said plungers to said guide means connecting said plungers to said slides, a second series of coin ejecting plungers to said slides, a second series of coin ejecting plungers confronting said first plungers, a common carrier for said second series of plungers, means supporting said connecting means for rearward and upward sliding movement, means supporting said carrier for vertical swinging movement, and operating means for said carrier, each of said first series of plungers upon rearward movement thereof also moving upwardly to thereby release a coin for gravitating movement after the coin has been substantially completely ejected from said guide.
11. A coin change delivering device comprising a plurality of coin magazines, a coin delivering slide for each magazine, a coin guide for receiving a coin to be changed, a series of coin engaging plungers movable relative to said guide means connecting said plungers confronting said first plungers, a common carrier for said second series of plungers, means supporting said connecting means for rearward and upward sliding movement, means supporting said carrier for vertical swinging movement, a resilient locking member fixed to said carrier and movable therewith over the upper open end of said guide for closing the latter during a coin changing operation, and operating means for said carrier, each of said first series of plungers upon rearward movement thereof also moving upwardly to thereby release a coin for gravitating movement after the coin has been substantially completely ejected from said guide.
